UNITED STATES PATENT OFFICE.

JOHN A. PARTEN AND ROBERT PARTEN, OF MINNEAPOLIS, MINNESOTA.

TRAFFIC SIGNAL.

Application filed May 7, 1923. Serial No. 637,080.

Our invention relates to traffic signals and more particularly to such signals for motor-propelled vehicles, and has for its object to improve the same in the several particulars 5 hereinafter noted.

To the above end, the invention consists of the novel devices and combinations of devices hereinafter described and defined in the claims.

10 In the accompanying drawings, which illustrate the invention, like characters indicate like parts throughout the several views.

Referring to the drawings:

Fig. 1 is a fragmentary perspective view 15 of an automobile having the invention applied thereto;

Fig. 2 is a view principally in horizontal section taken on the line 2—2 of Fig. 1 with some parts diagrammatically illustrated;

20 Fig. 3 is a detail view in section taken on the line 3—3 of Fig. 2, on an enlarged scale;

Fig. 4 is a detail view principally in section taken on the line 4—4 of Fig. 3;

25 Fig. 5 is a view principally in vertical section taken on the line 5—5 of Fig. 2, on an enlarged scale;

Fig. 6 is a detail view principally in section taken on the line 6—6 of Fig. 4;

30 Fig. 7 is a detail view in section taken on the line 7—7 of Fig. 4;

Fig. 8 is a detail view partly in plan and partly in section illustrating the controlling valve and the casing;

35 Fig. 9 is a detail view in section taken on the line 9—9 of Fig. 8;

Fig. 10 is a detail view in section taken on the line 10—10 of Fig. 8; and

Fig. 11 is a wiring diagram.

40 Of the parts of the automobile illustrated, it is only necessary to note the body 12, cowl 13, instrument board 14, intake manifold 15, vacuum tank 16, pipe line 17 leading from the intake manifold to the vacuum tank 16, and pipe line 18 leading from the gas tank, not shown, to the carburetor.

45 The numerals 19 and 20 indicate a pair of axially aligned cylinders, the inner ends of which are axially spaced and connected by a tube which affords a vacuum chamber 21. These cylinders 19 and 20 are formed in a horizontal pipe 22 which extends under the cowl 13 forward of the instrument board 14, and its ends terminate at the sides of 50 said cowl and have secured therein bushings

23. Said bushings 23 extend through the sides of the cowl 13 and are provided with body fittings 24 which rigidly hold the pipe 22 against endwise or turning movements.

Our invention includes left and right-hand 60 direction indicators that are identical, the one with the other, and independently operated; and for the sake of brevity, the left-hand direction indicator will be described in detail and the parts indicated by numerals 65 while corresponding parts of the right-hand indicator will be indicated by like prime numerals.

Mounted in the cylinder 19 is a valve-acting piston 25 having a tapered inner end 70 adapted to engage a correspondingly formed seat 26 in the inner end of said cylinder and close the same to the vacuum chamber 21. This piston 25 is provided to project and retract a direction indicator which includes a 75 cylindrical lamp casing 27 having a lamp socket 28 rigidly secured in the outer end of a hollow rod 29 mounted to slide endwise in the respective bushing 23 and secured to said piston. The lamp casing 27 is provided with front and rear lenses 30 and 31, respectively, the latter preferably being red, and a single contact electric light bulb 32, preferably held in the lamp socket 28 by the customary bayonet joint. 80

Extending transversely through the lamp casing 27, rearward of the light bulb 32, is a partition 33 having a central light opening 34, and which light opening is closed, when the left-hand direction indicator is retracted, by a gravity-opened shutter 35 to cut off the rear lens 31 from said light bulb. This shutter 35 is pivoted at 36 to the partition 33 and provided with a cam-acting extension 37 arranged to engage the respective bushing 23 and body fitting 24 during the retracting movement of the direction indicator and move said shutter into a position to close the light opening 34. When the direction indicator is projected, the cam-acting extension 37 is moved out of engagement with the respective bushing 23 and body fitting 24 and permits the shutter 35 to open under the action of gravity so that the lamp bulb 32 will illuminate the rear lens 31. The inner end of the hollow rod 29 extends axially through the piston 25, and its inner end is closed by a plug 38. 100

105 The piston 25 is operated by creating a partial vacuum in the cylinder 19 at one 110

end of said piston and opening the cylinder at the other end of said piston to the atmosphere. As one means of thus operating the piston 25, a T 39 is substituted for the customary L which connects the pipe line 17 to the vacuum tank 16, and to this T is attached a pipe 40 which opens into a valve casing 41 located just forward of the instrument board 14. Mounted in the valve casing 41 is a rotary tapered valve 42 having a stem 43 rotatably mounted in a detachable cap 44 on said valve casing. A coiled spring 45 encircles the stem 43, is compressed between the valve 42 and cap 44, and yieldingly holds said valve seated. The valve stem 43 extends through the instrument board 14 and is provided with a knob 46 by which it may be turned.

Formed in the top of the valve casing 41 are three circumferentially spaced radial ports 47 that are open to the atmosphere, and in the bottom of said casing are three circumferentially spaced radial ports 48, 49 and 49'. A radial port 50 is formed in the valve 42 and arranged to be brought into registration in any one of the ports 47 by turning said valve. This port 50 is provided with two diverging branch ports 51 and 51', the former of which is arranged to be brought into registration with either of the ports 48 and 49, and the latter of which is arranged to be brought into registration with either of the ports 48 and 49' by turning the valve 42. An L-shaped port 52 is also formed in the valve 42. One end of this port, to wit, the one that extends longitudinally of said valve 42, opens into the valve casing 41 for communication with the pipe 40, and the other or radial end of said port is arranged to be brought into registration with any one of the ports 48, 49 or 49' by turning the valve 42.

A pipe 53 is attached to the valve casing 41 and connects the port 48 with the vacuum chamber 21, and pipes 54 and 54' are also attached to said valve casing and connect, respectively, the port 49 to the forward end of the cylinder 19, and the port 49' to the forward end of the cylinder 20. Normally, the valve 42 is positioned to cause a partial vacuum to be created in the vacuum chamber 21 from the vacuum tank 16 through the pipe 40, valve casing 41, ports 52 and 48 and pipes 53, and to open the cylinders, forward of the pistons, to the atmosphere through the ports 50, 51 and 49 and pipe 54 to the cylinder 19 and the ports 51' and 49' and pipe 54' to the cylinder 20. It will thus be seen that with a partial vacuum at the inner ends of the pistons and atmosphere pressure at the outer ends thereof, said pistons are held retracted and in engagement with the seats 26.

The valve 42 is yieldingly held in a normal position by a spring pressed friction

pin 55 mounted in said valve and provided with a conical point which extends into a correspondingly formed seat 56 in the valve casing. This pin 55 also engages a pair of stop pins 57 secured to the valve casing 41 to limit the turning movement upon either side of normal position. A rubber bumper 58 is placed in the outer end of the cylinder 19 to cushion the piston 25 at the limit of its projecting movement to prevent the same from rebounding and thereby partially retract the direction indicator.

To project the left-hand direction indicator, the knob 46 is operated to turn the valve 42 until stopped by the engagement of the pin 55 with the left-hand stop 57. This turning of the valve 42 causes the port 50 to register with the right-hand port 47, and the branch port 51' to register with the port 48 which opens up the vacuum chamber 21 to atmospheric pressure and closes the cylinder 19, forward of its piston, to atmospheric pressure and opens the same to the vacuum tank 16 so that a partial vacuum is created thereon, and at which time the atmospheric pressure in the vacuum chamber 21 will move the piston 25 outward in the cylinder 19 and thereby project the left-hand direction indicator.

To retract the left-hand direction indicator, the valve 42 is returned to normal position and thereby opens up the cylinder 19, forward of the piston, to atmospheric pressure and creates a partial vacuum in the vacuum chamber 21 and cylinder 19, at the inner end of the piston, thereby causing the atmospheric pressure, forward of the piston 25, to move the same to the inner end of said cylinder.

The projecting and retracting movements of the right-hand direction indicator are the same as those of the left-hand direction indicator with the exception that the valve 42 is turned in the opposite direction.

To automatically light the lamps 32 and 32' at the time the direction indicators are projected to indicate the direction in which the vehicle is about to turn and put said lights out when the direction indicators are retracted, the following electrical connections from the storage battery 59 of the vehicle or from any other suitable source of electrical energy are provided, to wit:

The main circuits from the battery 59 are indicated by the numerals 60 and 61, the former of which is grounded as indicated, and the latter of which, at its outer end, is extended through an insulating core 62 and connected to a tubular switch guide 63 which extends longitudinally within the vacuum chamber 21. This switch guide 63 is supported and held out of engagement with the walls of the vacuum chamber 21 by a pair of axially spaced insulating cores 64 and 64' in said chamber. The insulating core 62

extends radially from the vacuum chamber 21 intermediately between the cores 64 and 64' and is mounted in a nipple 65 screwed into the pipe 22, the tube affording the 5 vacuum chamber 21, and a filler-acting collar 66 interposed between said pipe and tube. Said cores have peripheral air ducts.

The main circuit 61 is in the form of an insulated wire, from the outer end of which 10 is stripped the insulation and the bare wire is inserted through a bore in the core 62. To secure the wire 61 in the core 62, the outer end of said core is longitudinally split and clamped onto said wire by an internally 15 tapered nut 67 applied to the outer end of the nipple 65. The inner end of the core 62 is cut away to expose the bare wire 61 and permit the same to bear directly on the metal switch guide 63.

20 An automatic main switch 68 in the form of a rod is slidably mounted in the left-hand end of the switch guide 63 and is yieldingly held projected by a coiled spring 69 which encircles said switch guide and is compressed 25 between a collar on said rod and the core 64. The inner end of the main switch 68 is bent laterally and works through a longitudinal slot in the guide 63 for engagement with the fixed member 70 of a longitudinally 30 extensive and contractible contact. This fixed contact member 70 is in the form of a thin flat bar which is telescoped into the movable member 71 of said contact, and which member 71 is in the form of a flat tube 35 that has wiping contact with the fixed member 70 during the projecting and retracting movements of the left-hand direction indicator. The fixed contact member 70 is anchored by extending the same through the 40 core 64 and then bending the same laterally for engagement with the switch 68 and is held in place by a key 72.

When the left-hand direction indicator is 45 retracted, the main switch 68 is engaged by the insulating plug 38 in the piston 25, and is held retracted, against the tension of the spring 69, to hold its laterally bent end out of engagement with the fixed contact member 70, as shown in Fig. 4. The movable contact member 71 extends longitudinally 50 through the piston rod 29 and is supported and held out of contact therewith by mounting its inner end in the insulating plug 38 and securing its outer end to an insulating core 73, in the inner end of the lamp socket 28, by means of a binding screw 74. The connection from the binding screw 74 to the lamp 32 is in the form of a spring pressed 55 headed plunger 75 mounted in an insulating core 76 secured in the outer end of the lamp socket 28. When the lamp 32 is inserted into its socket 28, the headed plunger 75 is retracted against the tension of its spring 77 which yieldingly holds said lamp so that the 60 bayonet joint which connects the same to

the lamp socket will not release said lamp. The spring 77 has direct contact between the binding screw 74 and the plunger 75 and completes the electrical connection between the same.

70 From the above description it is evident that during the initial projecting movement of the left-hand direction indicator the automatic switch 68 is released as the piston 25 moves away from the same and said switch 75 moved by the spring 69 into engagement with the fixed contact member 70 to complete the electrical connection from the battery 59 to the lamp 32. It is likewise evident that the lamp 32 will remain lighted 80 until a switch 68 is moved out of engagement with the fixed contact 70 during the final retracting movement of the piston.

85 Further electrical connections are provided for keeping the lamp 32 and 32' lighted while driving in the night so that they may be used as side lights or used as parking lights by partly projecting the direction indicators.

90 These further connections include a branch circuit 78 which extends from the main circuit 61 to a switch guide 79 identical with the switch guide 63 and mounted in the cores 64 and 64' and held parallel to the switch guide 63. The outer end of the branch circuit 78 has its insulation stripped therefrom, and the bare wire inserted through a bore in the core 62 and held in the same manner that the main circuit wire 61 is held. The core 62 is further cut away at its 95 inner end to expose the bare branch wire 78, and which wire bears directly on the switch guide 79.

100 Mounted in the left-hand end of the switch guide 79 is an automatic secondary switch 80 identical with the main switch 68 and held projected by a coil spring 81. When the piston 25 is retracted, the auxiliary switch 80 is also held retracted against the tension of its spring 81 and is in engagement with an extension 82 on the movable contact member 71. When the piston 25 is projected, the released auxiliary switch 80 is also projected by its spring 81 and moved until stopped by the engagement of its relatively short laterally bent end with the insulating plug 38. Interposed in the branch circuit 78 is a manually operated switch 83 which is open except when the lamps are used as side lights or parking lights. Obviously, when the switch 83 is closed, the circuit will be completed from the battery 59 to the lamp 32 when the piston 25 is in its innermost position, and at 115 which time the main switch 68 is open.

120 When the direction indicators are projected to indicate the direction in which the vehicle is about to turn, the shutters 35 and 35' are automatically opened so that the rear red lenses are illuminated by the lamps 130

32 and 32', thus making the indicators easily visible from the rear of the vehicle. Likewise, the red lenses will be illuminated when the direction indicators are projected only a slight distance and used as parking lights. When the lamps are used as side lights, the shutters are closed so that the red lenses will not be visible.

The above described invention has, in actual usage, proven highly efficient for the purpose had in view, and it only requires a slight movement of the knob 46 on the instrument board to project or retract either one of the direction signals, and when said signals are retracted, the lamp casings are closely positioned to the cowl and give the vehicle a neat and finished appearance.

It is important to note that the fixed contact member 70 is anchored in the plug 64, off center, and extends into the movable contact member 71 which in turn extends through and is anchored in the plug 38, off center, and thereby holds the piston 25 from turning in the cylinder 19, and which piston, through its rod 29, holds the lamp casing 27 from turning so that the lenses 30 and 31 are always properly positioned. Of course, the lamp casing 27 is held by the fixed contact member 70' in the same manner.

30 What we claim is:

1. A traffic signal comprising a cylinder and a co-operating piston, means including a controlling valve for creating a partial vacuum in the cylinder at one end of the piston and for exposing to atmospheric pressure the other end of the piston and for alternating the same, and a direction indicator arranged to be operated by the piston, said controlling valve being normally set so that there is a constant partial vacuum at one end of the piston and a constant atmospheric pressure at the other end thereof to cause said piston to hold the direction indicator inoperative.

45 2. A traffic signal comprising a cylinder and a co-operating piston, means including a controlling valve for creating a partial vacuum in the cylinder at one end of the piston and for exposing to atmospheric pressure the other end of the piston and for alternating the same, a direction indicator arranged to be operated by the piston, and resilient means for stopping the piston at the limit of its movement to render the direction indicator operative.

60 3. A traffic signal comprising a cylinder, a vacuum chamber having communication with the cylinder, a valve-acting piston in the cylinder and normally closing the vacuum chamber thereto, means including a controlling valve for creating a partial vacuum in the vacuum chamber and for opening to atmospheric pressure the cylinder at the opposite end of the piston from the chamber and for alternating the same,

and a direction indicator arranged to be operated by the piston.

4. A traffic signal comprising two cylinders, a vacuum chamber having communication with said cylinders, a valve-acting piston in each cylinder and normally closing the vacuum chamber thereto, means including a controlling valve for creating a partial vacuum in the vacuum chamber and selective to open to atmospheric pressure either cylinder at the opposite end of its piston from the vacuum chamber and for alternating the same, and two direction indicators arranged to be independently operated by the pistons.

5. A traffic signal comprising a cylinder and a co-operating piston, a direction indicator arranged to be actuated by the piston, a valve casing, a controlling valve in the casing, a main conduit leading to said casing, means for creating a partial vacuum in the main conduit, and branch conduits leading from the valve casing and opening into the cylinder at each end of the piston, said valve being arranged to connect either of the branch conduits to the main conduit to operate the piston and render the direction indicator operative or inoperative at will, said controlling valve being normally set so that there is a constant partial vacuum at one end of the piston and a constant atmospheric pressure at the other end thereof to cause said piston to hold the direction indicator inoperative.

6. The structure defined in claim 5 in which the valve is operative to open either of the branch conduits to atmospheric pressure.

7. A traffic signal comprising two cylinders, a piston in each cylinder, a vacuum chamber having communication with said cylinders at one of the ends of the pistons, two direction indicators arranged to be independently operated by the pistons, a valve casing, a controlling valve in said casing, a main conduit leading to the valve casing, means for creating a partial vacuum in the main conduit, and branch conduits leading from the valve casing to the vacuum chamber and from the valve casing to the cylinders at the opposite ends of the pistons from the vacuum chamber, said valve being arranged to connect either of the branch conduits to the main conduit to operate the piston and render the direction indicators operative or inoperative at will, said controlling valve being normally set so that there is a constant partial vacuum at one end of the piston and a constant atmospheric pressure at the other end thereof to cause said piston to hold the direction indicators inoperative.

8. A traffic signal comprising two cylinders, a valve-acting piston in each cylinder, a vacuum chamber having communication with said cylinders at one of the ends of

5 said pistons, said pistons normally closing the vacuum chamber to the cylinders, two direction indicators arranged to be independently operated by the pistons, a valve casing, a controlling valve in the valve casing, a main conduit leading to the valve casing, means for creating a partial vacuum in the main conduit, and branch conduits leading from the valve casing to the vacuum chamber and from the valve casing to the cylinders at the opposite ends of the pistons from the vacuum chamber, said valve being arranged to connect either of the branch conduits to the main conduit and 10 to open either of said conduits to atmospheric pressure to independently operate the pistons and render the direction indicators 15 operative or inoperative at will.

9. A traffic signal including a lamp casing having front and rear lenses and a lamp, means for projecting and retracting the lamp casing, and an automatic shutter in the lamp casing arranged to open when the lamp casing is projected and to close when 20 the lamp casing is retracted to cut off the lamp from the rear lens.

10. The combination with the body of a motor-propelled vehicle, a traffic signal mounted on said body including a lamp casing, means for projecting and retracting the 25

lamp casing at one side of the vehicle body, said casing having front and rear lenses and a lamp, and an automatic shutter in the lamp casing arranged to open when the lamp casing is projected and to close when 30 the lamp casing is retracted to cut off the lamp from the rear lens.

11. The combination with the body of a motor-propelled vehicle, a traffic signal mounted on said body including a lamp casing, means for projecting and retracting the lamp casing at one side of the vehicle body, 35 said casing having front and rear lenses and a lamp, and a gravity opened shutter arranged to be automatically closed during the 40 retracting movement of the lamp casing to cut off the lamp from the rear lens.

12. In a vehicle, the combination with two cylinders extending transversely thereof, and co-operating pistons in said cylinders, 45 of lamps carried by the pistons, said pistons normally holding the lamps close to the sides of the vehicle to afford side lights, and means for operating the pistons to project the lamps to afford direction signals and for 50 retracting the same.

In testimony whereof we affix our signatures.

JOHN A. PARTEN.
ROBERT PARTEN.
